US00D361664S

United States Patent [19]

Brown

[11] **Patent Number:** Des. 361,664[45] **Date of Patent:** ** Aug. 29, 1995[54] **LADDER CADDY**[75] Inventor: **Harry L. Brown**, 2224 Beech St.,
Virginia Beach, Va. 23451[73] Assignees: **Harry L. Brown; Lyle L. Tatroe**, both
of Virginia Beach, Va.[**] Term: **14 Years**[21] Appl. No.: **16,752**[22] Filed: **Dec. 23, 1993**

4,730,802 3/1988 Chatham et al. 248/238

Primary Examiner—Louis S. Zarfas*Assistant Examiner*—Catherine R. Oliver*Attorney, Agent, or Firm*—Griffin, Butler, Whisenhunt & Kurtossy[57] **CLAIM**The ornamental design for a ladder caddy, as shown
and described.**DESCRIPTION****FIG. 1** is a top perspective view of a ladder caddy in
accordance with this invention with a side, ladder-
engaging, slide-out handle being in a fully-inserted position
and a center, or top, handle being in a deployed,
upwardly-directed, position;**FIG. 2** is a top plan view of the ladder caddy of **FIG. 1**;
FIG. 3 is an end elevational view of the ladder caddy of
FIG. 1;**FIG. 4** is a cross-sectional view taken on line IV—IV in
FIGS. 2 and 3;**FIG. 5** is a cross-sectional view taken on V—V in **FIG.**
4;**FIG. 6** is a side elevational view of the ladder caddy of
FIG. 1, with the side ladder engaging, slide-out handle
being fully deployed outwardly and the ladder caddy
shown mounted on an A-frame ladder which is depicted
in broken lines and forms no part of the claimed design;
and,**FIG. 7** is taken from the right of **FIG. 3** with a hook
portion of the handle being shown in cross-section on
line VII—VII in **FIG. 3**.**Related U.S. Application Data**[63] Continuation-in-part of Ser. No. 839,495, Feb. 20, 1992,
abandoned, and a continuation-in-part of Ser. No. No.
777,105, Oct. 16, 1991, abandoned.[52] U.S. Cl. .... **D3/315**[58] Field of Search **D3/315, 308, 309, 307;**
